WRENCH

Leighton Leigh, Fremont, Mich., assignor to Air
Control Products, Inc., Muskegon, Mich., a cor-
poration of Michigan

Application February 3, 1939, Serial No. 254,371

1 Claim. (Cl. 81—15)

The present invention relates to a wrench and more particularly to a wrench for altering the angular inclination of the fins of a sheet metal grille.

The primary objects of the instant invention are to provide a device of the character above indicated whereby the angular inclination of the fins of a sheet metal grille may be conveniently and readily altered, either before or after installation of the grille in connection with its duct; to provide such a wrench whose jaws are adjustable lengthwise adapting it for use in altering the angular disposition of sheet metal grille fins of varying lengths; to provide such a wrench having a stop adapted to engage the grille whereby its sheet metal fins may all be altered from their original angular disposition to a different predetermined angular inclination; and, to provide such a wrench which is efficient in use and economical in manufacture.

Illustrative embodiments of the invention are shown in the accompanying drawings, wherein:

Figure 1 is a face or plan view of a sheet metal grille adapted for installation in connection with an air duct and whose angularly inclined fins are stamped therefrom and integrally formed therewith;

Figure 2 is an enlarged sectional view thereof on line 2—2 of Figure 1 and showing one form of wrench adapted for altering the original angular inclination of the grille fins;

Figure 3 is a perspective view of the wrench per se;

Figure 4 is another perspective view of a modified form of wrench;

Figure 5 is a perspective view of a second modified form of wrench whose jaw lengths may be adjustably fixed to adapt it for use in connection with grilles having fins of varying lengths;

Figure 6 is an enlarged sectional view on line 6—6 of Figure 5;

Figure 7 is a fragmentary plan view of the wrench shown in Figure 3 but having a stop fixedly secured thereto whereby the fins of the grille may all be altered from their original angular disposition to a different predetermined angular inclination; and

Figure 8 is a view of the wrench shown in Figure 7, partly in section and showing the manner in which it is adapted for use.

Referring then to the drawings wherein like parts of the grille structure and its fin altering wrenches are designated by the same numerals in the several views, the rectangular grille 10 formed from stamped sheet metal is provided

with a plurality of transversely disposed fins 11, 12, the fins 11 being all disposed at substantially the same angular inclination and the fins 12 being all disposed at a different angular inclination whereby the air flowing therethrough and from a duct with which the grille is associated is directionally controlled.

The T-shaped wrench 13 shown in Figure 3 having a pair of spaced elongated jaws 14, 15 of a length substantially equal to the length of 10 the fins 11, 12 may be applied to the individual fins in the manner indicated in Figure 2 for altering their original angular disposition to a different angular inclination, either before or after installation of the grille in connection with a 15 duct and for the purpose of directionally altering the flow of air therethrough.

The modified form of wrench 16 shown in Figure 4 is provided with two pairs of oppositely disposed jaws 17, 18 likewise adaptable for application to the individual fins in the manner shown in Figure 2 and since the spaced pairs of its jaws engage the opposite ends of the lengths of a fin to which it is applied, the angular inclination of the fin may be conveniently altered 25 thereby.

A second modified form of wrench 19 is shown in Figures 5 and 6 wherein the oppositely disposed pairs of jaws 20, 21 are longitudinally slidably adjustable by means of the bolt 22 disposed 30 within the slots 23, 24 and its manually turnable wing nut 25 which adjustable wrench is adapted for use in connection with grilles having fins of varying lengths.

The wrench 26 shown in Figures 7 and 8 is the 35 wrench shown in Figure 3 but provided with the stop 27 adapted to engage the grille fins 11 as shown in Figure 8 for altering the original angular disposition of the fins to a different predetermined angular inclination.

It will thus be seen that the wrenches herein shown and described are admirably adapted to alter the original angular disposition of the fins of a grille throughout their entire lengths and without distortion of portions thereof since the 45 entire length of the fin or substantial portions thereof at its opposite extremities are engaged by the jaws of the wrench.

While but several specific embodiments of the invention have been herein shown and described, 50 it will be understood that certain details of the constructions shown may be altered or omitted without departing from the spirit of this invention as the same is defined by the following claim.

I claim:

A T-shaped wrench whose leg provides a handle and whose head comprises a pair of longitudinally slidably adjustable members, each member having a pair of spaced jaws projecting laterally therefrom at its outer end, each pair of

jaws being adapted to engage the opposite sides of an integrally formed fin of a sheet metal grille and adjacent its opposite extremities for altering the original angular disposition of the fin to a different angular inclination.

LEIGHTON LEIGH.
